UNITED STATES PATENT OFFICE.

JOHN W. CANNON, OF BIRMINGHAM, ALABAMA.

BURIAL GARMENT.

Application filed September 15, 1925. Serial No. 56,502.

This invention relates to a burial garment, more particularly to a suit of clothing for males, and has for its object to provide, in a manner as hereinafter set forth, a comparatively inexpensive garment of the class referred to and having the elements thereof, such as the coat, vest and trousers so constructed as to be quickly and conveniently positioned on the corpse, and furthermore when so positioned having the appearance of a regular tailor made suit combined with shirt, collar, cuffs and necktie.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a front elevation of a coat, vest, shirt, collar, cuffs and tie, forming elements of a burial garment in accordance with this invention.

Figure 2 is an elevation of the trousers forming an element of a burial garment in accordance with this invention.

Figure 3 is an elevation of one of the sections of the coat forming an element of a burial garment looking towards the front thereof.

Figure 4 is a view similar to Figure 3 looking towards the inner side of the section of a coat.

Figure 5 is an elevation of the vest looking towards the front and further showing the collar, tie and shirt.

Figure 6 is a rear elevation of the trousers in an open position.

A burial garment, in accordance with this invention, comprises a coat element formed of two sections referred to generally by the reference characters 1, 2, and each of said sections include a half collar 3 formed of an inner and an outer fold, a front 4 provided with lapel 5 forming a continuation of the half collar, a back 6, a sleeve 7 and a half shoulder 8. The front 4 of the section 1, below its lapel, has a set of buttons 9 secured thereto in proximity to the vertical front edge thereof. The front 4 of the sec-

tion 2, below its lapel is formed with a series of superposed buttonholes 10 in proximity to the vertical front edge of said section, and said front is furthermore provided with an upper pocket 11, to one side of its lapel 5 and from which projects a handkerchief 12. The section 1, as well as the section 2, has secured to the inner face of its front, near its half collar, and in proximity to the bend from which the lapel extends, a snap fastener member. The function of the snap fastener member will be presently referred to, and that snap fastener member carried by the section 1 is indicated at 13 and the one carried by the section 2 is indicated at 14. Each of the coat sections is lined throughout as indicated at 15. The half collar 3 is formed of an inner and an outer fold. Secured to the inner face of the half collar 3 in proximity to the free end thereof and to the inner fold of the half collar is a snap fastener member 16. Secured to the half collar 3 on that face thereof opposite the face on which is arranged the snap fastener member 16, is a flexible tie member 18 which projects from the free end of the half collar 3. Arranged within and depending from each sleeve 7 is a cuff 19.

The vest element of the suit is formed of two sections and which are generally referred to by the reference characters 20, 21. Each vest section is formed from a tapered upper portion 22 and a triangularly shaped lower portion 23 which extends at right angles with respect to the upper portion 22. The lower portion 23 gradually decreases in width from the inner towards the outer end thereof and the outer end of each portion 23 has connected thereto a tie member 24. The inner end of the portion 23 of the section 20 has secured thereto, and on the outer face thereof, as well as in proximity to the inner edge of the section, a set of buttons 24' which extend through openings 25 formed in the lower portion 23 of the section 21 in proximity to the inner edge of the latter. The buttons 24' and openings 25 are arranged below the tapered portions 22 of the vest sections. The inner edge of each tapered portion 22, is upon a slight curve, as indicated at 26. The tapered portion 22 of the vest section 20, in proximity to the inner edge thereof has secured to its outer face a snap fastener member 27 and the tapered portion 22 of the section 21, has secured to its outer face in proximity to its

inner edge a snap fastener member 28 which opposes the member 27 when the vest sections are connected together by the buttons 24' engaging in the openings 25. The outer face of the upper end of the tapered portion 22 of the section 20 has secured thereto a snap fastener member 29 and a snap fastener member 30 is secured to the outer face at the upper end of the upper portion 22 of the section 21. The function of the snap fastener members 27, 28, 29 and 30 will be presently referred to. When the vest element is positioned, it has arranged at the upper portion thereof a collar 31, a shirt bosom 32 and a tie 33. The tapered upper portion 22 of the vest sections surround the collar 31 and partly conceal the shirt bosom 32, as well as concealing the lower portion of the necktie 33. The garment or suit further includes 20 a pair of trousers referred to generally by the reference character 34. The trousers are made large and full and all seams are pressed. The trousers are of the closed front type and formed with an open back 35 and 25 at the waist portion 36 of the trousers, a hem 37 is provided through which extends a shirring or draw string 38. The string 38 is of a length to project from each end of the hem 37 so that the ends thereof can be 30 tied together when desired.

When the suit is positioned the trousers are applied and secured together at the back thereof through the medium of the string 38. The vest, shirt bosom and tie with collar are positioned separately. The coat sections are applied separately. After the coat sections are applied the tie members 18 are connected together and the snap fastener members 13, 14 are detachably connected respectively to the snap fastener members 27, 28. The snap fastener member 16 of the coat section 1 is connected to the snap fastener member 29 of the vest section 20 whereby said coat section 1 and vest section 45 20 are secured together. The snap fastener member 16 of the coat section 2 is detachably connected to the snap fastener member 30 of the vest section 21 whereby said sections 2 and 21 are secured together. From 50 the construction and arrangement of each of the several elements of the suit, it is obvious that the suit can be quickly and conveniently applied to the corpse and further when applied will have the appearance of a 55 regular tailor made suit combined with shirt, collar, cuffs and necktie. The tie members 24 are tied together to secure the vest element in position around the body.

It is thought that the many advantages

of a burial garment, in accordance with this invention can be readily understood, and although the preferred embodiment of the invention is as illustrated and described, yet it is to be understood that changes in the details of the several elements can be had which will fall within the scope of the invention as claimed.

What I claim is:—

1. In a burial garment, a coat element formed of two sections, each consisting of a half collar having an inner and an outer fold, a front formed with a lapel providing a continuation of the outer fold of the half collar, a back, a sleeve and a shoulder, said front, shoulder and back forming continuations of the inner fold of the half collar, flexible means secured to one face and extending from the free end of the half collar for connecting one section to the other, a fastener element secured to the inner face of the inner fold of the half collar near the free end of such fold for securing a section against the rear face of the back of the collar of a vest, and a fastener member arranged on the inner face of the front in proximity to the point of mergence of the inner fold of the half collar with the front for securing the latter to one side of the upper portion of the front of the vest.

2. A burial garment comprising two similar and separate coat sections, each formed of a folded half collar consisting of an inner and an outer fold, each of said sections having a flexible tie extended from one face at the rear end of the half collar thereof, said ties providing means for connecting said sections together, two similar and separate vest sections, each formed with a half collar at one end and a laterally disposed triangular shaped lower portion provided with a flexible tie, the ties of said vest sections providing means for connecting them together at the rear thereof, said coat and vest sections having interengaging means positioned for securing the inner face of the front of each coat section to and in proximity to the inner side of the front face of a vest section at the upper portion of the latter, and said coat and vest sections having interengaging means positioned on the upper ends of the vest sections and inner faces of the half collars of the coat sections for connecting the inner folds of the half collars to the half collars of the vest sections.

In testimony whereof, I affix my signature hereto.

JOHN W. CANNON.
